UNITED STATES PATENT OFFICE.

WILLIAM F. GEHRIG, OF NEWARK, NEW JERSEY, ASSIGNOR TO ESSEX SPECIALTY CO., INC., OF BERKLEY HEIGHTS, NEW JERSEY, A CORPORATION OF NEW JERSEY.

WIRELESS-TELEPHONE RECEIVING APPARATUS.

Application filed May 11, 1922. Serial No. 560,036.

To all whom it may concern:

Be it known that I, WILLIAM F. GEHRIG, a citizen of the United States, residing at Newark, in the county of Essex and State of New Jersey, have invented certain new and useful Improvements in Wireless-Telephone Receiving Apparatus; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in wireless telephone apparatus; and, more particularly, to a novel arrangement and mounting of tuning coil and detector devices for wireless telephone receiving sets.

The invention has for its principal object to provide a novel and simple arrangement and mounting of cylindrical tuning coil together with a novel rotary slider switch for cooperation therewith; and the invention has for a further object to provide a neat, simple, cheap and efficient arrangement and mounting of said tuning coil devices together with suitable detector devices for association therewith.

Other objects of this invention, not at this time more particularly enumerated, will be clearly understood from the following detailed description of the same.

With the various objects of this invention in view, the same consists, primarily, in the novel tuning coil and detector set for wireless telephone receiving apparatus herein-after set forth; and, furthermore, the invention consists in the novel arrangements and combinations of the various devices and parts, as well as in the details of the construction thereof, all of which will be hereinafter more fully described and claimed.

The invention is clearly illustrated in the accompanying drawings, in which:

Figure 1 is a side elevation of the apparatus made according to and embodying the principles of this invention, a part of the casing being shown in vertical section to disclose the parts enclosed within the same.

Figure 2 is a plan view of the apparatus. Figure 3 is a bottom plan view of the

casing top or cover upon which the apparatus is mounted.

Figure 4 is a detail fragmentary vertical longitudinal section, taken on line 4-4 in Figure 2, the same being drawn on an enlarged scale.

Figure 5 is a bottom plan view of the rotary slider switch handle and its pointer member.

Figure 6 is a perspective view of a spacer block used in connection with the means for fastening the tuning coil element to the underside of the casing top or cover.

Figure 7 is a perspective view of the switch or contact arm of the rotary slider switch element.

Similar characters of reference are employed in all of the hereinabove described views, to indicate corresponding parts.

Referring now to said drawings, the reference character 8 indicates a suitable casing or box, the upper open end of which is closed by a top or cover member 9, which fits said upper open end and which may be suitably secured thereto.

The reference character 10 indicates a suitable hollow cylindrical core, made of insulating material, upon which the wire windings 11 of the tuning coil element are supported. Said core 10 is secured to the underside of said top or cover member 9, so as to be suitably suspended and spaced therefrom, in such manner that the tuning coil element is enclosed within the interior of the casing or box 8 beneath the top or cover member 9. The means for so mounting the tuning coil element within the casing, comprises a pair of bolts 12 and 12' which pass downwardly through the top or cover member 9. Arranged upon the shanks of said bolts are the respective perforate spacer pieces or blocks 13 and 13' which abut upon the under side of said top or cover member 9. The free lower ends of the bolts 12 and 12' extend through the walls of the core 10, adjacent to the respective ends of the latter, and the said core is secured against displacement from the ends of the bolts by the respective curvilinear washer members or clips 14 and the fastening nuts 15 screwed upon the shanks of said bolts.

As thus secured to the cover or top member 9, and suspended from the under or inner side thereof, the tuning coil element is so

disposed that the upper surface of its coil windings 11 are spaced from the underside of said cover or top member.

Mounted in connection with said cover or top member 9 is a rotary slider or tuning switch mechanism adapted to cooperate with the tuning coil element. This mechanism comprises a vertical spindle 16 journaled in a bearing opening 17 provided in said cover 10 or top member, and suitably located relative to the position of the tuning coil so as to be disposed in off-set relation to one side thereof opposite a point intermediate the ends of the same. The upper end of said 15 spindle 16, which projects exteriorly from said casing, is provided with a threaded extension 18 of reduced diameter. The reference character 19 indicates a handle or knob of insulating material, which possesses, in 20 imbedded relation to its lower end, a centrally alined internally threaded socket-piece 20, into which said threaded extension 18 screws to operatively attach the handle or knob 19 to the exterior end of said spindle 25 16. Engaged against the bottom of said handle or knob 19 is a pointer plate 21, having a central perforation 22 and a pair of upwardly pressed tits or studs 23. Integrally connected with said pointer plate to extend outwardly therefrom is a pointer arm 30 24. Said pointer plate is secured to the handle or knob and to the spindle, so as to turn therewith, by passing the spindle extension 18 upwardly through the central perforation 22, so as to engage and clamp the pointer 35 plate between the bottom of the handle or knob and the shoulder 25 at the juncture of the spindle body and its extension 18, the tits or studs 23 being countersunk in the 40 body of the handle or knob to thereby prevent turning of the pointer plate and its pointer arm relative to the handle or knob and the spindle. Disposed between the underside of said pointer plate and the upper 45 surface of said top or cover member 9 is a washer 26. Arranged against the underside of said top or cover member 9 is a contact plate 27 having a perforate end 28 through which the spindle 16 extends. Said spindle 50 is provided with a transverse opening 29 adjacent to its lower inner end adapted to receive the butt 30 of a laterally projecting switch or contact arm 31, which extends over the upper side of the tuning coil element so as to be movably and electrically engageable with wire windings 11 thereof. Arranged upon said spindle 16 above the butt 30 of said switch or contact arm 31 is a washer 32, and arranged around said spindle 16, intermediate the perforate end 28 of 55 said contact plate 27 and the washer 32 is a coiled compression spring 33, which normally exerts a downward thrusting pressure upon said spindle 16, whereby the switch or contact arm 31 is yieldably held in flexed po-

sition to maintain the same tensionally engaged with the windings of the tuning coil element. Fixed upon the upper surface of the top or cover member 9, in position to cooperate with the pointer arm 24 is a scale 70 plate 34, whereby the pointer indicates the adjusted position of the switch or contact arm relative to the windings of the tuning coil element. There are also mounted on the upper side of the top or cover member 9, one 75 on either side of the pointer arm 24, a pair of stop pins 35 which limit the movement of the pointer arm in each direction, and consequently limit the rotation of the handle and spindle to determine the limit of adjustment of the switch or contact arm 31 toward each end of the tuning coil element.

Mounted upon the upper surface of said top or cover member 9 is a crystal detector body 36 and holder 37 therefor, together 80 with an adjustable cat-whisker contact arm 38 and holder or mounting 39 therefor.

Fixed upon said top or cover member 9, at one side thereof are binding posts 40 and 41, and at the opposite side additional binding 90 posts 42 and 43. The binding post 40 is connected by a suitable lead 40' to the holder 37 of the detector body 36, and by an additional lead 40'' to one end of the windings 11 of the tuning coil element. The cat 95 whisker contact arm holder or mounting 39 is connected by a suitable lead 42' with the binding post 42. Interconnecting the binding post 43 with the binding post 41 is a ground wire lead 44 which crosses over the 100 contact plate 27, and which is secured in fixed electrical engagement with the latter by soldering the same thereto.

The incoming conductor 45 leading from the aerial or antennæ of a wireless telephone receiving outfit is connected with the binding post 40, so that the wave impulses are caused to enter the detector body 36 through the lead 40', passing thence through the cat whisker contact arm and its holder 110 115 by way of the lead 42' to the binding post 42; at the same time said wave impulses are carried to the tuning coil windings 11 through the lead 40'', passing thence through the switch or contact arm 31 to the spindle 16 and contact plate 27, and through the ground wire lead 44 to the binding post 41, which is connected to a suitable ground by the conductor 46. The phones (not shown) are connected at one side by the 120 conductor 47 with the binding post 42, and at the other side, by the conductor 48 with the binding post 43 being thence grounded through the ground lead wire 44, binding post 41 and conductor 46 upon a suitable 125 ground connection.

From the above description it will be apparent that the present invention provides a very neat, compact and simple construction, arrangement and hook-up of tuning 130

coil and detector devices for wireless telephone receiving sets.

One of the important advantages afforded by the novel structure lies in the provision 5 of the rotary slider switch adapted to co-operate with the windings 11 of the tuning coil. The novel arrangement of such feature permits the enjoyment of all the convenience and simplicity of operation entailed in turning 10 a knob or handle, as against the more crude and inconvenient "arms-length" or longitudinal slider and bar arrangement, while at the same time permitting the enclosure and protection of the coil and its 15 windings within a casing and concealed from view. The inherent tension of the switch or contact arm 31, together with the auxiliary tension applied thereto through the coiled compression spring 33, assures a 20 perfect electrical engagement of the switch or contact arm with windings of the longitudinal coil, in all positions of said switch or contact arm relative to said windings, while at the same time the indication of the 25 adjusted position of the switch or contact arm relative to said windings is conveniently and visibly shown by the position of the pointer arm 24 relative to the scale plate 34.

I am aware that some changes may be 30 made in the various arrangements and combinations of the devices and parts, as well as in the details of the construction of the same, without departing from the scope of this invention as set forth in the foregoing 35 specification, and as defined in the appended claims. Hence, I do not limit my invention to the exact arrangements and combinations of the various devices and parts as described in said specification, nor do I confine myself 40 to the exact details of the construction of said parts as illustrated in the accompanying drawings.

I claim:

1. In a device of the kind described, a 45 casing, a cover for said casing, a cylindrical tuning coil element, means for supporting said tuning coil element within said casing from the under side of said cover but spaced downwardly from the latter, a vertical spindle journaled in said cover, a knob on the exterior end of said spindle for turning the same, a laterally projecting switch contact arm on the interior end of said spindle having its free end portion tensionally bearing on the upper surface of the windings of said tuning coil and adjustably movable from end to end of the latter when said spindle is turned, and means for connecting said spindle and switch contact arm with 50 ground.
2. In a device of the kind described, a 55 casing, a cover for said casing, a cylindrical tuning coil element secured to the under side of said cover within said casing, means 60 for spacing said tuning coil element from the under surface of said cover, a vertical spindle journaled in said cover, a knob on the exterior end of said spindle, a contact plate on the under side of said cover through which said spindle extends, a laterally projecting switch contact arm on the interior end of said spindle having its free end portion tensionally bearing on the upper surface of the windings of said tuning coil, a compression spring around said spindle 65 intermediate said contact plate and the butt of said switch contact arm to thrust downwardly on said spindle to augment the tension of said switch contact arm relative to said tuning coil element, and said contact 70 plate serving to receive the attachment of a ground lead in electrical connection with said spindle and its switch contact arm.
3. In a device of the kind described, a casing, a cover for said casing, a cylindrical tuning coil element secured to the under side of said cover within said casing, means for spacing said tuning coil element from the under surface of said cover, a vertical spindle journaled in said cover, a knob on the exterior end of said spindle, a contact plate on the under side of said cover through which said spindle extends, a laterally projecting switch contact arm on the interior end of said spindle having its free end portion tensionally bearing on the upper surface of the windings of said tuning coil, a compression spring around said spindle 75 intermediate said contact plate and the butt of said switch contact arm to thrust downwardly on said spindle to augment the tension of said switch contact arm relative to said tuning coil element, and said contact 80 plate serving to receive the attachment of a ground lead in electrical connection with said spindle and its switch contact arm.
4. In a device of the kind described, a 85 casing, a cover for said casing, a cylindrical tuning coil element secured to the under side of said cover within said casing, means for spacing said tuning coil element from the under surface of said cover, a vertical spindle journaled in said cover, a knob on the exterior end of said spindle, a contact plate on the under side of said cover through which said spindle extends, a laterally projecting switch contact arm on the interior end of said spindle having its free end portion tensionally bearing on the upper surface of the windings of said tuning coil, a compression spring around said spindle 90 intermediate said contact plate and the butt of said switch contact arm to thrust downwardly on said spindle to augment the tension of said switch contact arm relative to said tuning coil element, said contact plate serving to receive the attachment of a ground lead in electrical connection with said 95 spindle and its switch contact arm, and co-operating means connected with said knob and the outer surface of said cover to indicate the adjusted position of said switch contact arm relative to the windings of said tuning coil element.
5. In a device of the kind described, a 100 supporting member, a cylindrical tuning coil secured to the under side of said supporting member in downwardly spaced relation thereto, a vertical spindle journaled in said supporting member, a knob on the exterior end of said spindle, a laterally projecting switch contact arm on the interior end of said spindle having its free end portion tensionally bearing on the upper surface of the windings of said tuning coil, a compression spring around said spindle 105 intermediate said supporting member and the butt of said switch contact arm to thrust downwardly on said spindle to augment the tension of said switch contact arm relative to said tuning coil, and means for connecting said spindle and switch contact arm to ground.

- 4
5. In a device of the kind described, a supporting member, a cylindrical tuning coil secured to the under side of said supporting member in downwardly spaced relation thereto, a vertical spindle journaled in said supporting member, a knob on the exterior end of said spindle a laterally projecting switch contact arm on the interior end of said spindle having its free end portion tensionally bearing on the upper surface of the windings of said tuning coil, a compression spring around said spindle intermediate said supporting member and the butt of said switch contact arm to thrust 15 downwardly on said spindle to augment the tension of said switch contact arm relative to said tuning coil, means for connecting said spindle and switch contact arm to ground, and cooperating means connected 20 with said knob and the upper side of said supporting member to indicate the adjusted position of said switch contact arm relative to said tuning coil.
6. The combination with a cylindrical tuning coil of a rotary slider switch comprising a vertical spindle having a laterally projecting resilient contact arm connected therewith, the free end portion of said contact arm being adapted to tensionally bear 25 upon the windings of said coil, spring means for exerting an axial thrust upon said spindle to augment the tension of said contact arm, and a knob on said spindle for turning the same.
- 30 7. The combination with a cylindrical tuning coil of a rotary slider switch comprising a vertical spindle having a laterally projecting resilient contact arm connected therewith, the free end portion of said contact arm being adapted to tensionally bear 35 upon the windings of said coil, spring means for exerting an axial thrust upon said spindle to augment the tension of said contact arm, a knob on said spindle for turning the same, and means for connecting said spindle and contact arm to ground. 40
8. The combination with a cylindrical tuning coil of a rotary slider switch comprising a vertical spindle having a laterally projecting resilient contact arm connected therewith, the free end portion of said contact arm being adapted to tensionally bear 45 upon the windings of said coil, spring means for exerting an axial thrust upon said spindle to augment the tension of said contact arm, a knob on said spindle for turning the same, and means for connecting said spindle and contact arm to ground. 50
9. The combination with a cylindrical tuning coil of a rotary slider switch comprising a vertical spindle having a laterally projecting resilient contact arm connected therewith, the free end portion of said contact arm being adapted to tensionally bear 55 upon the windings of said coil, spring means for exerting an axial thrust upon said spindle to augment the tension of said contact arm, a knob on said spindle for turning the same, means for connecting said spindle and contact arm to ground, and indicator means associated with said spindle and its knob for showing the adjusted position of said contact arm relative to said tuning coil. 60

In testimony, that I claim the invention set forth above I have hereunto set my hand this 2nd day of May, 1922.

WILLIAM F. GEHRIG.
